William Christiaensen of New York N. Y.
Letters Patent No 3335 Dated Decr 26. 1865
Design for a Masonic group of Statues

The subject referred to in these letters Patent and making part of the same.

To all to whom it may concern:

Be it known that I William Christiaensen
of the City of New York, in the State and County of New York,
have originated and invented a new design for a Masonic
group and statue, of which the following is a full, clear and
exact description, reference being had to the accompanying
specimens or drawings making part of this specification.

A monumental group of the Virgin with Time en-
folded in the ringlets of her hair. On the front of the group
there are two broken pieces of a pillar. Behind the pillar
stands a half naked virgin holding an urn resting on a book
in her left hand, and a branch of acacia in her uplifted right hand.
Time with wings and a scythe resting on his
left shoulder, ~~holding her hair with his left hand and~~
an hour glass at his feet.

Claims

What I claim as my invention and for which I
desire letters patent from the United States, is the design as
above described for Masonic Group or Statue.
